(57) **CLAIM**

The ornamental design for a carrying case for an optical fiber fusion splicer, as shown and described.

DESCRIPTION

FIG. 1 is a front view of a carrying case for an optical fiber fusion splicer.

FIG. 2 is a rear view of the carrying case for an optical fiber fusion splicer.

FIG. 3 is a top plan view of the carrying case for an optical fiber fusion splicer.

FIG. 4 is a bottom view of the carrying case for an optical fiber fusion splicer.

FIG. 5 is a right side view of the carrying case for an optical fiber fusion splicer.

FIG. 6 is a left side view of the carrying case for an optical fiber fusion splicer.

FIG. 7 is a perspective view of the carrying case for an optical fiber fusion splicer.

FIG. 8 is a top plan view with the lid open of the carrying case for an optical fiber fusion splicer.

FIG. 9 is a perspective view with the lid open of the carrying case for an optical fiber fusion splicer.

FIG. 10 is a perspective view with the workbench mounted on the front portion of the carrying case for an optical fiber fusion splicer; and,

FIG. 11 is a reference view with the workbench detached of the carrying case for an optical fiber fusion splicer.

The broken line showing of the carrying case for an optical fiber fusion splicer is for the purpose of illustrating environmental structure and forms no part of the claimed design.
